UNITED STATES PATENT OFFICE.

HARVEY G. SHAFER, OF INDIANAPOLIS, INDIANA.

GEAR GRINDER.

Application filed April 25, 1924. Serial No. 708,864.

My invention relates to improvements in gear grinding or cutting machines and has for one of its objects that of providing an improved means for automatically feeding the work to the cutter for the cutting or grinding of gear teeth. Another object of my invention is to provide means for automatically indexing the gear to present a new tooth to be cut after the cutting operation has been completed on the preceding tooth.

Other objects and advantages of my invention will appear more fully hereinafter.

For the purpose of describing my invention I have illustrated one embodiment thereof in the accompanying drawings in which.

Fig. 1 is a side elevation of a gear grinding machine embodying my invention.

Fig. 2 is a plan view thereof;

Fig. 3 is a sectional view taken on the line 3—3 of Fig. 2;

Fig. 4 is a sectional view taken on the line 4—4 of Fig. 2;

Fig. 5 is an enlarged detail plan partly in section of the work-supporting and indexing mechanism;

Fig. 6 is a sectional view taken on the line 6—6 of Fig. 5;

Fig. 7 is a sectional view taken on the line 7—7 of Fig. 5;

Fig. 8 is a detail perspective of the guiding and indexing rack.

In the embodiment of the invention illustrated, I provide a suitable base or table 1^a, which carries a supporting arm 2 having mounted thereon the usual grinding wheel shaft 3 supporting and driving the grinding wheel 4. The shaft 3 is preferably mounted in a head of the usual construction which permits various angular adjustments of the grinding wheel. So much of the structure comprises the usual bed and grinding wheel of the commercial type of universal grinder now in use for various purposes.

Mounted on the table 1^a is a supplemental base 1 secured to the table 1^a by bolts or keys 1^b and provided with sliding bed 5 which is adapted to reciprocate substantially longitudinally of the axis of the grinding wheel.

This bed 5 is provided with the usual undercut beveled guideways 6 engaging corresponding guideways 7 on the base 1 to insure accurate movement of the table and prevent the same from vertical displacement. This bed 5 is elevated above the base 1 to provide a clearance between the underside of the top

and the bed and the top of the base 1 to accommodate the spacing and indexing mechanism for the gear.

The gear to be ground is rotatably mounted on a supporting and clamping bench which comprises a hub support 8 having a base 9 resting on the top of the table 5 over an opening 10 in said table and provided with an annular flange 11 fitting within said opening to properly position the base and the hub. A spindle 12 extends through the hub, being rotatably mounted therein in suitable bushings 13 and the upper end of this spindle is provided with an integral collar 14 adapted to rest upon the top of the hub 8, a washer being interposed between the collar and the top of the hub. The spindle 12 is extended beyond this collar and is adapted to support the blank 16 to be cut or ground. This blank fits on a bushing 17 surrounding the top end of the spindle, which bushing at its lower end rests on the collar 14, a washer 18 being interposed between the bottom of the blank and an annular flange 19 on the bushing. The gear blank is clamped in position on the upper end of the spindle between the collar 14 and a clamping member 20 which is held clamped down on the top of the hub of the blank by means of a screw nut 21 threaded on the top of a screw 22 which in turn is threaded into the end of the spindle.

The master gear 24 is supported on the lower end of the spindle 12, being adapted to be clamped between a nut 25 threaded on the lower end of the spindle and a shoulder on the spindle 12, a washer 26 interposed between the gear and the bottom end of the hub support.

By the above construction, it will be noted that the master gear and blank form a unitary structure in which the master gear and blank may be clamped together, and this unitary structure may be mounted on the sliding bed 5 by means of suitable bolts 27.

The master gear is adapted to have rolling engagement with a guiding and indexing rack 28 composed of two sections 28^a and 28^b, one of which, the section 28^b is movable relatively to the other and with the sliding bed 5, while the other is relatively stationary with respect to the bed. This rack is mounted on a sliding rack table 29 supported on the base 1, being adapted to fit in a beveled slot in said base and movable at

right angles to the line of movement of the bed 5 in order to adjust the rack to gears of different sizes. To this end, in a bracket 30, offset from the base 1, I provide a stop screw 31 which is screw-threaded in the bracket and provides at its inner end, a stop for limiting the outer movement of the table 29 so that, by rotating the stop screw 31, the position of the table 29, and with it 10 the rack 28, may be nicely adjusted. After the stop screw has been adjusted, it may be held in its adjusted position by a set screw 32. In order that the table 29 may be moved to disengage the rack 28 from the master 15 gear to permit a free rotation of the gear blank for the purpose of inspection, etc., during the grinding operation, I provide a sliding bolt 33 likewise mounted in the bracket 30. The top of this bolt is provided with 20 a socket 34 adapted to receive an eccentric pin 35 on a vertically extending spindle 36 mounted in a journal 37 above the bolt. A handle 38 is provided for rotating the spindle and it will be noted that one side 25 of the journal is extended to form a stop 39 to be engaged by the handle and for preventing the rotation of the spindle beyond a predetermined point. This sliding bolt is connected by a stem 40 which, at its inner 30 end is threaded into a screw threaded socket in the end of the table 29 so that the length of the connection between the bolt and the table may be adjusted to correspond to the adjustment of the stop screw 31. The stem 35 is provided, on one side, with a stationary collar 42 which abuts against the bolt 33 whereby, as the bolt is moved inward, the stem and with it the sliding table will receive a corresponding movement. A coil 40 spring 43 is interposed between the opposite end of the collar and the knurled end 44 of the stem 40, which spring resiliently holds the table against the stop screw 31 when the spindle is rotated to move the table out- 45 wardly. By this resilient holding means, in event of foreign particles becoming interposed between the teeth of the gear and tooth of the rack, the rack may move relatively to the gear without destroying 50 the holding parts of the table.

The movable section 28^b of the rack 28 overlaps the stationary section on the line 45 for a distance of two teeth and this movable section is provided with a lip 46 seating into a socket 47 on a slide bar 48 provided at its outer end with an extension stem 49 having an adjustable stop nut 50. This nut is adapted to be engaged by a downwardly extending flange 51 on the end 60 of the bed 5 after the bed has been moved a predetermined distance. Carried by the bed is a cam 52 adapted to engage a pin 53 on a spring pressed latch finger 54. This finger, when the bed is retracted to the right, looking at Fig. 5, is released by the

cam 52 and allowed to project into a socket 55 on the slide bar 48 to hold the slide bar in its retracted position and as the end of the finger 54 is slightly tapered to fit the correspondingly tapered socket 55 the slide bar is properly spaced, thereby properly spacing the section 28^b of the rack. As the bed 5 is retracted to the left, looking at Fig. 5, the cam 52 will engage the pin 53 retracting the finger 54 to permit the slide bar to be moved forward when the flange 51 of the bed engages the coil spring 56 surrounding the stem 49. 70 75

The bed 5 is reciprocated by means of a cam wheel 57 having a cam slot 58. This cam slot is engaged by a roller supported upon a pin 59 mounted in a slide bar 60 which slide bar is in turn provided with a clamp 61 arranged to clamp on a link arm 62 secured to the bed 5. This cam wheel is mounted on a shaft supported in suitable bearings 62 carried by a base 63 which like the base 1 is clamped on the table 1^a by screws or keys 64. By thus mounting the gear carrying and indexing mechanism on the supplemental bases I provide a self-contained unitary structure which may be used with the present type of commercial grinding machine without modification of the machine.

In operation, the master gear and the blank to be ground are clamped in position on the clamping bench, the nuts 21 and 25 at the opposite ends of the spindle 12 serving to clamp the master gear and blank on the spindle while permitting the spindle to rotate in the hub support 8. Care is exercised in clamping the two gears on the spindle to insure the teeth of the blank being in perfect alignment with the teeth of the master gear. The unit thus formed is then bolted to the sliding bed 5 by means of the bolts 27 which extend through the base of the hub support 8 and into the top of the sliding bed. After the blank and master gear are mounted on the sliding bed 5 the rack 28 is adjusted into engagement with the master gear. The rotation of the cam wheel 57 reciprocates the bed 5 projecting the same to the right, looking at Fig. 1, during which

sliding movement the master gear makes rolling engagement with the rack 28. This rolling engagement of the master gear with the rack rotates the spindle and imparts a corresponding rotation to the blank so that the blank moves into engagement with the grinding wheel with a rolling movement. One face of one tooth, or if desired, opposite faces of two teeth, are then ground by the wheel and as the sliding table continues in its movement to the right the master gear makes engagement with the movable section 28^b of the rack and passes off of the relatively stationary section. At this time the nut 50 is engaged by the flange 51 of the 130

moving table and the section 28^b of the rack moves with the sliding bed 5 so that, during the rest of the movement of the bed 5, the master gear will not be rotated. During this forward movement of the pin 53 on the latch finger 54 rides off the cam member 52 and is projected into the socket in the bar 48, thus holding the movable section 28^b of the rack stationary during a portion of the 10 turn movement of the bed 5. The effect of this is the equivalent of advancing the movable section 28^b of the rack one tooth so that, during the return reciprocating movement of the bed, the master gear will have been 15 advanced one tooth relatively to the rack section 28^a and a new tooth, upon the further reciprocation of the bed will be presented to the grinding wheel. By the time the flange 51 has moved to compress the 20 spring 56 and the cam 52 moved to disengage the latch finger 54, the master gear will have been rotated into engagement with the stationary section 28^a of the rack and the movable section 28^b will then move to its initial 25 position without affecting the master gear.

While I have shown and described my invention as being used for grinding blanks which have already been cut, it is obvious that the same may be used for initially cutting blanks. In this event, a rotary cutter 30 will be substituted for the grinding wheel.

In order to maintain the movable section 28^b in perfect alignment with the stationary section 28^a of the rack 28, the movable section 28^b is provided with a tongue 63 sliding 35 in a groove 64 in the table 29. This construction prevents any tendency on the part of the rack section 28^b from moving transversely to the section 28^a.

40 I claim as my invention:

1. In a gear grinding machine the combination with a grinding wheel, of a sliding bed, means for reciprocating said bed relatively to said wheel, a master gear rotatably mounted on said bed, means for supporting a blank to rotate with said master gear, a rack with which said master gear has rolling engagement during the reciprocation of said bed and a second rack movable relatively to 45 said first rack and arranged to be moved to rotate said gear independently of the first rack after the blank has moved out of engagement with the grinding wheel.

2. In a gear grinding machine the combination with a grinding wheel, of a sliding bed, means for reciprocating said bed relatively to said grinding wheel, a master gear rotatably mounted on said bed, means for mounting a blank to rotate with said master gear, a rack relatively stationary with respect to said bed and with which the master gear makes rolling engagement during its reciprocation and means operated by the movement of said bed for rotating said 50 master gear independently of said rack after

the blank has moved out of engagement with the grinding wheel.

3. In a gear grinding machine the combination with a grinding wheel, of a sliding bed, means for reciprocating said bed relatively to said grinding wheel, a master gear rotatably mounted on said bed, means for securing a blank to rotate with said gear, a two section rack with which said master gear is arranged to make rolling engagement during the reciprocation of said bed, one of said sections being relatively stationary to the bed and the other section being arranged to be moved with the bed during a predetermined portion of its movement to rotate the 75 master gear independently of said first rack section.

4. In a gear grinding machine, the combination with a grinding wheel, of a sliding bed, means for reciprocating said bed relatively to said grinding wheel, a master gear rotatably mounted on said bed, means for securing a blank to rotate with said master gear, a rack relatively stationary with respect to said bed and with which the master 85 gear makes rolling engagement during the reciprocation of said bed, means operated by the reciprocation of said bed for rotating said master gear independently of said rack and means for adjusting said rack to accommodate 90 gears of different sizes.

5. In a gear grinding machine the combination with a grinding wheel, of a sliding bed, means for reciprocating said bed relatively to said grinding wheel, a master gear 100 rotatably mounted on said sliding bed, means for securing a gear blank to rotate with said master gear, a rack having a part relatively stationary with respect to said sliding bed and a part movable with said sliding bed to rotate said gear independently of said stationary part and means for adjusting said rack to accommodate gears of 105 different sizes.

6. In a gear grinding attachment for 110 grinding machines, the combination with a base, of a rack transversely adjustable on said base, a bed longitudinally reciprocable on said base, and a blank and master gear carrier bodily removably mounted on said 115 sliding bed and adapted to support said master gear in engagement with said rack to cause the same to be rotated when the sliding table is reciprocated and means on said base for rotating said master gear independently of the rack.

7. In a gear grinder the combination with a grinding wheel, of a base, a sliding bed reciprocally associated with said grinding wheel, a rack stationarily mounted with respect to said sliding bed, a master gear and blank support for supporting said master gear in engagement with said rack and the blank in a position to be engaged by said 125 grinding wheel comprising a hub removably 130

mounted on said sliding table, a shaft mounted in said hub, means for removably securing a master gear at one end of said shaft in a position to engage said rack and means for securing a blank at the other end of said shaft in a position to be engaged by said grinding wheel, said hub shaft and master gear and blank comprising a self-contained unitary structure bodily removable from said sliding table.

8. In a gear grinder the combination with a grinding wheel, of a base, a rack transversely adjustable on said base, a sliding table longitudinally reciprocable on said base, means for supporting a master gear and blank on said sliding table with the

master gear in a position to be engaged by said rack and the blank in position to be engaged by said grinding wheel, means for positioning said rack carrying table with the rack in definite relation to the master gear, means for manipulating said rack carrying table to disengage the same from said master gear without affecting said positioning means, and means for rotating said master gear independently of said rack.

In witness whereof I, HARVEY G. SHAFFER, have hereunto set my hand at Indianapolis, Indiana, this 21st day of April, A. D. one thousand nine hundred and twenty four.

HARVEY G. SHAFFER.
